UNITED STATES PATENT OFFICE.

HARRY H. STYLL, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

OPHTHALMIC MOUNTING.

1,262,714.

Specification of Letters Patent. Patented Apr. 16, 1918.

Application filed October 6, 1917. Serial No. 195,015.

To all whom it may concern:

Be it known that I, HARRY H. STYLL, a citizen of the United States, residing at Southbridge, in the county of Worcester and 5 State of Massachusetts, have invented certain new and useful Improvements in Ophthalmic Mountings, of which the following is a specification.

This invention comprehends new and useful improvements in ophthalmic mountings and relates particularly to an improved form of mounting or frame of what is commonly known as the combination type made up of combined metal and xylonite or other 10 non-metallic parts.

One of the main objects of this invention relates to an improved frame having novel means for uniting and securely retaining against relative movement the metallic and 15 non-metallic parts.

Another object of the invention is the provision of a mounting of this character wherein the non-metallic ring is of a continuous unbroken piece while the metallic 20 member may be constructed of either a continuous member or a split ring as desired and applied to the non-metallic member in such a manner as to securely clamp the lens in its operative position.

With the above and other objects in view, the invention consists in the novel features of construction and the combination and arrangement of parts to be hereinafter more 25 fully described, pointed out in the claims and shown in the accompanying drawings, in which—

Figure I is a front elevation of a pair of eyeglasses illustrating my improved mounting.

Fig. II is a transverse sectional view through the frame at II-II in Fig. I.

Fig. III is a front elevation of a frame illustrating a modified form of the invention.

Fig. IV is a cross section on the line III-III of Fig. III.

Fig. V is a side elevation of the metallic member illustrating a modified form of fastening means.

Fig. VI is a cross section on the line V-V of Fig. V.

Fig. VII is a side elevation of the metal-

lic member illustrating still another modified form of the invention.

Fig. VIII is a cross section illustrating a 55 modified form of fastener.

Fig. IX is a sectional view showing another method of attaching the fittings to the metallic rim.

In carrying out my invention I provide a 60 frame 1 which includes the non-metallic ring 2 and the metallic ring 3. This non-metallic ring 2 is preferably made of xylonite or any similar material and includes the main body portion 4 having formed within its inner 65 face a circumferential groove 5 having inclined walls, said groove being adapted to receive the circumferential edge of the lens. 6. It will be understood that the annular portion 7 projecting beyond the groove 5 70 contains sufficient resiliency to permit the lens 6 to be forced through the same and into the groove 5, the inclined portions 8 of the lens abutting the inclined walls of the groove to prevent any lateral movement of 75 the lens after being forced into the groove.

As clearly illustrated in Fig. II the body 4 of the non-metallic ring 2 is provided upon one side thereof with the angularly projecting annular flange 9 and arranged within 80 this flange is the metallic ring 3 which is of a continuous piece. This metallic ring 3 when in position is securely held against relative movement by means of the small screw members 10 which extend through the 85 annular flange 9 and into the ring 3. While I have illustrated the use of screws 10 as the preferred form of fastening devices it will be understood that rivets or similar means may be used. The use of the screws as 90 means for securing the metallic and non-metallic rings together is preferred in view of the fact that they can be readily removed to detach the ring 3 from the ring 2. It will be apparent that when the ring 3 is in 95 position within the flange 9 it will tend to retain the annular portion 7 in a normal outstanding position and thus keep the lens 6 within its proper position, however it will be understood that with a little force the lens 6 can be readily forced beyond the annular member 7 and into the groove 5 and can also be removed by pressing outwardly on the lens near the flange thus forcing the edge of

the lens out beyond the portion 7 so as to entirely remove the lens from the ring.

In Fig. I it will be apparent that the temples 11 and nose bridge 12 are connected to my improved frame through the medium of the clips 13 which may be of any well known, but preferably of the type illustrated in the drawings which are disposed nearly around the frame 1 which will aid 10 in retaining the two rings in their relative positions with respect to each other.

In Figs. III and IV I have illustrated a modified form of the invention wherein the metallic ring 3' is split as shown at 14 and 15 adapted to be sprung into position within the flange 9. It will be noted that the outer face of the ring 3' is provided with a plurality of spurs or pointed lugs 15 which, when the ring 3' is placed in position, will engage with the flange 9. After the ring 3' is placed in position within the flange 9 the meeting ends of the ring as shown at 14 are to be finished over so as to provide a smooth appearance. It will be apparent from the foregoing that the ring 3' can be quickly and readily removed from within the flange 9 or placed in position. While I have shown these spurs 15 as merely pointed projections it will be apparent that they may be made in any desirable form such as shown in Figs. V and VI. In Fig. V I have illustrated a continuous bead 16 formed on the ring 3' substantially within the center of the surface and provided with a sharpened edge adapted to be embedded within the material of the ring 2 when the ring 3' is arranged within the flange 9. In Fig. VII I have illustrated a plurality of transversely disposed sharpened beads 17 which 40 act in the same manner as the spurs 15 or the bead 16 in retaining the ring 3' in its proper position.

From the foregoing description taken in connection with the accompanying drawings, the construction and advantages of my improved metal and non-metallic frame should be readily apparent, and it will be seen that I have provided and improved the frame which will present a neat and attractive appearance on the face and wherein the lens 8 may be quickly and readily arranged in position within the frame or easily removed therefrom. In my improved construction the metallic or stiffening ring is also arranged whereby it may readily be placed in position and connected to the ring 2 and at the same time may be removed in an equally short space of time. It will be understood that this improved 60 frame may be used in connection with either spectacles or eye-glasses without any change in the construction and arrangement of the various parts.

I claim:

1. A mounting including a ring, having

an inner circumferential groove, a lens adapted to be disposed within the groove, a second ring arranged within the first ring and arranged adjacent the lens and fastening members extending through the first ring and into the second ring to secure the second ring within the first.

2. A mounting including a ring comprising a body portion having an inner circumferential groove, an annular portion adjacent the groove, a lens adapted to be forced past the annular portion into the groove, a second ring disposed within the first ring adjacent the lens and means for securing the second ring within the first.

3. A mounting including a ring comprising a body portion having an inner circumferential groove, an annular portion disposed adjacent one side of the groove, a second ring disposed within the first ring and arranged adjacent the groove and fastening means extending through the first ring and into the second ring to secure the second ring within the first.

4. A mounting including a ring comprising a body portion, having an inner circumferential groove to receive the edge of a lens, an annular portion on the body adjacent the groove, a flange on the body opposite the annular portion, a second ring removably arranged within the flange and means for detachably connecting the second ring with the flange.

5. A mounting including a ring comprising a body portion, having an inner circumferential groove to receive a lens, an annular portion on the body adjacent the groove, a flange on the body opposite the annular portion, a split ring removably arranged within the flange and means carried by said split ring for engagement with the material of the flange to hold the split ring in place.

6. A mounting including a non-metallic ring comprising a body portion, having the inner circumferential groove to receive the edge of a lens, an annular portion on the body adjacent the groove, a flange on the body opposite the annular portion, a metallic ring removably arranged within the flange and means for detachably connecting the metallic ring with the flange of the non-metallic ring.

7. A frame member for an ophthalmic mounting, comprising an outer non-metallic rim member having a pair of grooves formed in the inner face thereof, one of said grooves being adapted to receive a lens, and a supplemental bracing member fitting within the other of said grooves.

8. In an ophthalmic mounting, the combination with a pair of continuous unbroken non-metallic rims having interior lens receiving grooves formed therein, of lenses fitted within said grooves, metallic bracing

members interiorly engaging the non-metallic members for bracing the same and aiding in retaining the lenses within the grooves thereof, and a bridging member or center 5 rigidly secured to one of the members of each frame and serving to connect the pair of frames.

In testimony whereof I have affixed my signature, in presence of two witnesses.

HARRY H. STYLL.

Witnesses.
